Assistant Examiner — Messina L Smith

(57) **CLAIM**

The ornamental design for a boat deck track, as shown.

DESCRIPTION

FIG. 1 is a front elevation view of a boat deck track showing the new design;
 FIG. 2 is a right side elevation view thereof;
 FIG. 3 is a left side elevation view thereof;
 FIG. 4 is a front elevation view thereof;
 FIG. 5 is an enlarged front elevation view of a portion of the boat deck track shown in FIG. 4;
 FIG. 6 is an enlarged left side elevation view of a portion of the boat deck track shown in FIG. 3;
 FIG. 7 is an enlarged cross-sectional view of a portion of the boat deck track taken in the direction of line 7-7 of FIG. 4;
 FIG. 8 is an enlarged front elevation view of a portion of the boat deck track shown in FIG. 5; and,
 FIG. 9 is an enlarged cross-sectional view of a portion of the boat deck track taken in the direction of line 9-9 of FIG. 4. The broken line showing of the boat in FIGS. 1 and 2 illustrates environment and forms no part of the claimed design. All other broken lines illustrate portions of the boat deck track that form no part of the claimed design.
